[57] **CLAIM**

The ornamental design for an insulating wire fastening member for use on shingles or siding, as shown and described.

DESCRIPTION

FIG. 1 is a perspective view of a fastening member in accordance with the present invention, installed beneath a siding slab. The siding slabs and wire are shown in phantom for illustrative purposes only, not being part of my invention.

FIGS. 2 and 3 are perspective views from above and below of wire fastening members in accordance with the present invention, identical with that of FIG. 1, except that the plane of the insulating holder has been rotated through 90°.

FIG. 4 is a perspective view on an enlarged scale of an insulating fastening member identical with that shown in FIG. 1, looking down from above.

FIG. 5 is an enlarged cross-section view through the plane indicated by the arrows 5-5 of FIG. 4, indicating the insulating center portion, the section of the embodiments of FIGS. 2 and 3 being substantially identical.

FIGS. 6 and 7 are additional perspective views on an enlarged scale of the fastening member of FIG. 4, from above and below.

FIG. 1

FIG. 5

FIG. 2

FIG. 3

FIG. 4

FIG. 6

FIG. 7
